MUNSON SIGLER, OF PATERSON, NEW JERSEY.

Letters Patent No. 86,465, dated February 2, 1869.

IMPROVEMENT IN DEVICE FOR REGULATING THE TENSION ON THE WARP IN LOOMS.

The Schedule referred to in these Letters Patent and making part of the same

To all whom it may concern:

Be it known that I, MUNSON SIGLER, of Paterson, in the county of Passaic, and State of New Jersey, have invented a new and improved Method of Regulating the Warp-Tension in Weaving-Looms; and I do hereby declare the following to be a full, clear, and exact description of the same, reference being had to the annexed drawing, making part of this specification, in which—

Figure 1 is a side elevation, and

Figure 2, a rear elevation of a loom, with my improvement applied thereto.

The object of this invention is to maintain, automatically, a uniform tension upon the warp of the moving fabric, as it rises and falls, in the fabrication of the cloth.

This object I accomplish by the use of a series of rollers, fitted in a swinging frame, and applied to the loom so as to receive and hang in the warp with such a degree of weight as may be best adapted to the fabric to be woven, said swinging frame being provided with an adjustment by which the weight upon the warp may be increased or diminished, at the pleasure of the operator.

In the drawing—

A represents the frame of the loom, and

E represents a pair of cams, by which the upward and downward motion of the warp is obtained through the agency of levers, upon which said cams act, substantially in the manner shown, said levers being attached to the warp by means of rigging-cords, as shown.

The swinging frame above referred to is represented in the drawing by B.

It consists of two stands or brackets, which, in the drawing, are marked B, and the upper ends whereof are united by means of a connecting-rod reaching across the rear part of the loom, from one bracket to the other.

These brackets are provided with suitable bearings, to carry the journals on the ends of the rollers, of which there are three, arranged substantially as shown, and each of said brackets is made with a slotted foot, projecting inward, the slot in the foot of said brackets being made to receive the studs F upon which said swinging frame is supported, about which it swings or vibrates, and on which it is adjusted horizontally, to regulate the weight or tensile strain on the warp.

The vibrating brackets or stands B, in the drawing, are fitted with three rollers. The work, however, might be done with two, though not so well, without a different construction of stand or bracket.

The journals of the top or third roller do not have their bearings in the brackets. The roller simply lies on and between the two lower rollers, and is kept in position by means of a pair of hook-journals, C, which reach down and hook on one of the rods uniting the brackets, and which are fitted with nuts at their tops, under which there are springs, made of any suitable material, and in any suitable form, by which means this top roller can be adjusted to the bottom rollers, as closely as may be desired, to keep the warp in its place, while, at the same time, it can yield to any little inequality in the thickness of the warp, thus leaving the tension always the same, or as nearly so as can be desired in practice.

It has already been stated that the brackets B vibrate upon the studs F upon which they are supported, and it will be seen that the further they pull back, the greater will be the tension upon the warp, and that, if there were nothing to regulate or limit the vibration, the whole swinging frame might fall away forward or away back, entirely destroying its utility. It is therefore necessary to have some means of regulating its vibrations, that is, of fixing the points between which it shall vibrate.

This I accomplish by means of a notched bracket, D, which fits in and is bolted on corresponding notches in the top of the frame-post A, and which is made to project over the inside of the said post and embrace the stands or brackets B, in a slot or recess in which said stands vibrate, the hole through which the screw passes, to secure said brackets D to the frame, being made oblong, by which said brackets can be moved back or forth, to increase or diminish the tension, as the case may require.

Having now described the nature and extent of my invention,

I claim as new herein, and desire to secure by Letters Patent—

The tension-regulator, consisting of a frame, made and fitted with rollers and applied to the loom, and governed in its operation, all substantially as described, for the purpose of securing a uniform tension of the warp, as set forth.

MUNSON SIGLER.
